(**) Term: **14 Years**

(57) **CLAIM**

(21) Appl. No.: **29/334,525**

The ornamental design for a “body length measuring device for infants,” as shown and described.

(22) Filed: **Mar. 27, 2009**

DESCRIPTION

(30) **Foreign Application Priority Data**

Sep. 29, 2008 (EM) 001010755

FIG. 1 is a top left front perspective view of the body length measuring device for infants in accordance with our new design;

(51) **LOC (9) Cl.** **10-04**

FIG. 2 is a top plan view thereof;

(52) **U.S. Cl.** **D10/70**

FIG. 3 is a left side elevation view thereof;

(58) **Field of Classification Search** D10/70;

FIG. 4 is a right side elevation view thereof;

33/511, 512, 515, 760, 783, 806, 809, 810;

FIG. 5 is a rear elevation view thereof;

177/245

FIG. 6 is a front elevation view thereof; and,

See application file for complete search history.

FIG. 7 is a bottom plan view thereof.
